MAGNETIC DEWATERING AND CONCENTRATING MEANS FOR MAGNETIC SEPARATORS

Henry K. Martin, Ironwood, Mich., assignor to Reserve Mining Company, Babbitt, Minn., a corporation of Minnesota

Application October 22, 1943, Serial No. 507,268

6 Claims. (Cl. 209—232)

1

The present invention relates to apparatus for separating mixed magnetic and non-magnetic materials from each other, and more particularly to a magnetic separator for separating magnetic ore concentrates and middlings from each other and/or from tailings.

The principal object of the invention is the provision of a novel and improved magnetic separator for separating mixed magnetic and non-magnetic materials, such as ore concentrates and middlings from each other and/or from tailings, which separator will not only be automatic in operation but will produce a drier and/or purer product or concentrate than separators heretofore known and used.

A more specific object of the invention is the provision of a novel and improved magnetic separator for separating magnetic ore concentrates and middlings from each other and/or from tailings and for dewatering the ore concentrates, wherein the material to be separated is caused to move under water in close proximity to the underside of an electric magnet but separated therefrom by a non-magnetic member and which includes magnet means located above the water and adjacent to the discharge end of the separator and below and spaced from the non-magnetic member for producing a high intensity magnetic field through which the material carried by the non-magnetic member must pass, whereby said material is temporarily retarded and/or diverted from the path which it would otherwise normally take, thereby effecting a better separation of the magnetic and non-magnetic material and a drier ore concentrate.

A further specific object of the invention is the provision of a novel and improved magnetic separator for separating under water magnetic ore concentrates and middlings from each other and/or from tailings and for dewatering the ore concentrates, wherein the material to be separated is caused to move under water in close proximity to the underside of a series of electric magnets but separated therefrom by a non-magnetic member and including means located adjacent to the discharge end of the separator above the water therein but below and spaced from the non-magnetic member for producing a magnet below said member having a high intensity magnetic field through which the material carried by the non-magnetic member must pass, whereby said material is temporarily diverted from the path which it would otherwise normally take, thereby effecting a better separation of the mag-

2

netic and non-magnetic material and a better dewatering of the ore concentrates.

The invention resides in certain constructions and combinations and arrangements of parts and further objects and advantages thereof will be apparent to those skilled in the art to which it relates from the following description of the preferred embodiment described with reference to the accompanying drawings forming a part of this specification in which similar reference characters designate corresponding parts, and in which

Fig. 1 is a longitudinal vertical section through a magnetic separator embodying the present invention; and

Fig. 2 is a section approximately on the line 2—2 of Fig. 1.

Referring to the drawings, the particular magnetic separator shown therein is of the general type shown in United States Patents to Robert E. Crockett, Nos. 2,003,430 and 2,090,112 and will not be herein described in detail. Suffice it to say that the separator shown comprises an irregularly-shaped tank or reservoir, designated generally by the reference character A, supported by a frame B, which frame also supports the magnet assembly C and the drums 10 and 11 which carry the endless conveyor 12. As shown, the tank A comprises a hopper 13 for receiving the tailings, a hopper 14 for receiving the middlings and a hopper 15 for receiving the ore concentrates in addition to the right-hand portion 16 where the material to be separated is fed to the separator and in turn to the conveyor 12.

The magnet assembly C comprises a plurality of magnets 17 having pole pieces 18 disposed closely adjacent to the upper side of the lower reach of the endless conveyor 12, which conveyor is made of non-magnetic material. Alternate pole pieces 18 are of different polarity and form a magnetic field having successive sections of opposite polarity through which the lower reach of the conveyor travels. The magnetic field produced by the magnets 17 extends substantially the entire length of the lower reach of the conveyor 12. In operation, water is maintained in the tank A up to about the level shown in the drawings and indicated by the reference character 20. The drums 10 and 11 which carry the endless conveyor 12 are keyed to shafts 21 and 22 located adjacent to opposite ends of the separator and rotatably supported in bushings 23 and 24, respectively, fixed to the channel irons 25 forming part of the frame B. Either or both of the shafts 21 and 22 may be driven as desired.

The lower reach of the conveyor 12 and the magnetic field produced by the magnet assembly C are substantially catenary in shape and the discharge end of the conveyor is located above the level of the water in the reservoir A with at least the intermediate section of the lower reach of the conveyor located below the level of the water. The entrance end of the conveyor 12 may be above or below the level of the water in the reservoir A as desired.

The magnetic and non-magnetic material to be separated is fed to the entrance or right-hand end 16 of the separator in any convenient manner as by a hopper 26 and is carried by water admitted along with the material through the hopper 26 and/or by separate means, such as the pipe 27, to a point underneath the right-hand end of the lower reach of the conveyor 12 and into the magnetic field produced by the magnets 17. The magnetic particles are carried along by the conveyor 12 while the tailings drop into the hopper 13. The middlings which are composed of both magnetic and non-magnetic material are carried along by the conveyor 12 to a point above the hopper 14.

According to the provisions of the present invention, a strong magnetic field is produced by means located underneath and spaced from the lower reach of the conveyor or belt 12 through which magnetic field material carried on the conveyor passes after it leaves the water. This magnetic field temporarily retards the travel of and rearranges the particles of material adhering to the conveyor 12 and causes some or all of them to temporarily leave the conveyor as they pass therethrough. As shown, a bar or member 30 of magnetic material is located underneath the lower reach of the conveyor 12 and spaced therefrom a short distance, thus forming a slot or aperture 31 through which material carried along by the conveyor must pass. Preferably the bar 30 is located intermediate adjoining poles 18 of the magnets 17 and being magnetized due to its location in the magnetic field formed by the magnets 17 cooperates therewith to produce a magnet underneath the conveyor 12, the poles of which magnet form high intensity magnetic fields at opposite sides of the bar through which fields the material adhering to the conveyor must pass. As the material carried along by the conveyor 12 enters the strong magnetic field adjacent to and produced by the bar 30 it tends to follow the path of greatest magnetism and part of it is attracted towards or to the bar. At the opposite side of the bar the magnetic material attracted away from the conveyor by the bar 30 again returns to the conveyor. A non-magnetic shield 32 located immediately above the bar 30 and extending a considerable distance on either side thereof prevents magnetic material from permanently adhering to the bar.

As previously mentioned, and more fully described in the Crockett Patent No. 2,090,112, the material to be separated is fed against the lower surface of the moving conveyor 12 at the right-hand end thereof (Fig. 1), whereupon the magnets 17 continuously attract and hold the magnetic material to the conveyor so that a continuous mat or strip of material is formed on the lower side of the conveyor and moved through the separator. This mat or strip of material will include some non-magnetic material which is mechanically held to the conveyor by the irregular shape of magnetic particles. However, as

the conveyor 12 advances past the pole pieces 18, the alternate polarity thereof will cause a constant rearrangement of the magnetic particles thus releasing some of the mechanically included, non-magnetic material, and also some of the less strongly magnetized particles, which drop into the hoppers 13 and 14. The tailings (constituted by the non-magnetic material) are not picked up and carried by the conveyor and hence drop directly into the hopper 13.

By the time the conveyor 12 has advanced the material clinging thereto to the point of emergency from the water in the separator, the appearance of the material will be somewhat hair-like. That is, the magnetic particles (which are individually very small in size) will be clinging to the underside of the conveyor 12 in chains or threads in the same manner as iron filings cling to the poles of a magnet. Hence, the water between adjacent chains or threads of the magnetic particles will immediately run off. However, considerable water and non-magnetic particles will be occluded in the lengths of the chains or threads of the particles and it is this water and non-magnetic material, as well as that between the chains or threads, which my improved apparatus effectively releases to produce a concentrate which is much drier and purer than that delivered by prior devices.

This improved dewatering and concentration, in the illustrated embodiment, results from the provision of the permeable bar 30 and the non-magnetic shield 32 adjacent the pole pieces 18. The bar 30 being within the magnetic field produced by the magnets 17, becomes an induced magnet and strengthens the magnetic field at that point. If the bar is directly below one of the pole pieces 18 of the magnets 17, the top of the said bar will have a pole of opposite polarity to that of the pole piece 18 thereabove. If the bar 30 be below and intermediate two of the pole pieces 18, there will be two magnetic poles induced in the top surface of the bar 30, one adjacent each side thereof, and each of opposite polarity relative to the adjacent poles 18.

The action of the bar 30 is, therefore, substantially the same whether the said bar be located exactly opposite a pole piece 18 or intermediate two such pole pieces. In either case, as the material and water carried by the conveyor 12 reach the region of the bar 30, a portion of the magnetic material leaves the conveyor and adheres to the shield 32 above the bar. This results from the fact that the lower ends of the chains or threads of particles carried on the conveyor 12 will be closer to the bar 30 than to the pole pieces 18 of the magnets 17 so that the former will have a greater influence on these lower particles than do the magnets 17. The magnetic particles so attracted to the shield 32 by the bar 30 will tend to build up thereon as a dam or dams (there being two dams if the bar be placed between two of the adjacent pole pieces).

The dam or dams so formed further restrict the relatively narrow gap 31 (defined by the shield 32 and conveyor 12) through which the material must pass with the result that the threads or chains of magnetic particles are both mechanically and magnetically disrupted, thus freeing the occluded water and non-magnetic particles which flow back to the hopper 14. Since the conveyor 12 is in continuous motion, the de-watered magnetic particles are carried away from the region of the bar 30 and the shield 32 as

new water-bearing material enters the region from the other side. The dam or dams formed on the shield 32 are, therefore, constantly depleted and rebuilt as the material leaves and enters the region with said dam or dams being maintained at substantially the same size. Thus, if the dams become too high the magnets 17 will have greater influence than bar 30 so that the upper particles are attracted to the conveyor 12. On the other hand, as the height of the dam or dams decrease, the magnetic effect of bar 30 upon the lower ones of the new particles brought into the region by the conveyor 12 will be sufficient to attract them to the shield 32 to replenish the said dam or dams. In the same manner, material is constantly being supplied to the right-hand end of the shield 32 (as viewed in Fig. 1) and the previously supplied material is removed from the left-hand end of the shield.

It will be apparent, therefore, that the bar 30 not only strengthens the magnetic field so as to produce a closer grouping of the particles in the region thereof, but also creates a condition productive of a mechanical rearranging of the particles so that the resulting concentrate is both purer and drier than that resulting from simply increasing the magnetic field (i. e., by increasing the current in the energizing coils of magnets 17) without the use of the bar 30 and shield 32.

The bar 30 and shield 32 may be supported in any convenient manner above the level of the water in the reservoir A and adjacent to the left or discharge end of the bottom of the catenary curve or shape taken by the lower reach of the conveyor 12. As shown, the bar 30 is fixed to the non-magnetic shield 32 which in turn is suspended from the magnet assembly C by the members 33 and 34 (see Fig. 2) and the shield 32 is constructed (as illustrated in Fig. 1) with a relatively flat section extending parallel with the travel of the conveyor.

In the preferred embodiment of the invention shown, a single bar 30 is shown just above the level of the water in the reservoir A and above the hopper 14 and a similar assembly, designated generally by the reference character 35, located also above the water in the reservoir but closer to the discharge point of the conveyor. The device 35 is similar in construction and operation to the bar assembly comprising the bar 30 and the shield 32 except for the fact that it comprises two bars 36 and 37 similar to the bar 30 located underneath a single shield or member 38. If desired, either or both ends of the shields may be bent downward. In practice, the height of the aperture 31, that is the distance between adjacent surfaces of the shield and conveyor, will vary depending upon the size, etc., of the material being separated. Distances of from $\frac{3}{4}$ " to $\frac{5}{8}$ " have been used satisfactorily with ore concentrates.

As previously described in detail, the purpose of the magnetic bars shown is to produce, in cooperation with the magnets 17, a magnet or magnets or a magnetic pole or poles underneath the conveyor creating a strong magnetic field or fields at the opposite side thereof through which material adhering to the conveyor 12 must pass and thereby be rearranged on the conveyor by temporarily being diverted in a direction away from the conveyor. Obviously the magnetic fields or effect referred to can be produced by means other than the permeable bars shown, as by either permanent or electric magnets, the poles of which terminate at about the location of the bars shown.

It is also to be understood that the means used to produce the strong magnetic field or fields can be located in any desired place along the lower reach of the conveyor 12 and that if bars and shields similar to those shown are used any suitable arrangement thereof may be employed. Upon test the product of a separator similar to that shown in the drawings, having a single permeable bar and shield like the bar 30 and shield 32 shown, located approximately in the position of the bar assembly 35 and having a $\frac{5}{8}$ " gap between the shield and the conveyor, contained 53.19% solids, of which 63.81% was iron, whereas the product of the same separator without the bar and shield assembly contained only 29.47% solids, of which only 62.44% was iron.

The preferred embodiment of the invention herein shown is merely illustrative of the invention and it is not to be considered as limited to the particular construction shown. The present invention can be applied to other types of separators and numerous changes can be made in the construction shown herein within the scope of the invention, as will be understood by those skilled in the art to which it relates, for example, the tank A may be of any desired shape and/or construction and may employ any known or desired baffle or hopper arrangement.

It will be apparent from the foregoing disclosure that the objects of the invention heretofore enumerated and others have been accomplished and that a new and improved magnetic separator especially adapted for separating ore concentrates and middlings from each other and/or from tailings has been provided which separator will produce a purer and drier product than magnetic separators heretofore known and used in the iron ore industry and it is my intention to hereby cover all adaptations, modifications and uses of the invention herein disclosed which come within the practice of those skilled in the art to which it relates and the spirit and scope of the appended claims.

Having thus described my invention, what I claim is:

1. In a magnetic separator for separating magnetic and non-magnetic material such as ore concentrates and middlings from each other and/or from tailings, the combination of: a reservoir or tank; means for supplying liquid to said tank; a flexible non-magnetic conveyor having a portion submerged in the liquid in said tank and a portion thereof adjacent to the discharge end of the separator disposed above the surface of said liquid; means for moving said conveyor; a plurality of magnets having pole faces disposed closely adjacent to the upper side of parts of said submerged portion and said non-submerged portion of said conveyor for producing a continuous magnetic field on the opposite side of said conveyor; means for feeding material to be separated to said tank and causing it to come in close proximity to the underside of said conveyor in said magnetic field whereby said magnetic field causes magnetic material in said mixture to engage and be carried along by said conveyor; magnet means located below said non-submerged portion of said conveyor and opposite said pole faces for producing a high intensity magnetic field through which material being carried along by said conveyor must pass and within which the material will concentrate thus expediting the removal of the liquid; and a non-magnetic member or shield interposed between said conveyor and said magnet means.

2. In a magnetic separator for separating magnetic and non-magnetic material such as ore concentrates and middlings from each other and/or from tailings, the combination of: a reservoir or tank; means for supplying liquid to said tank; a flexible non-magnetic conveyor having a portion of substantially catenary shape a part of which is submerged in the liquid in said tank; said conveyor having a portion of the catenary part thereof adjacent to the discharge end of the conveyor disposed above the surface of said liquid; means for moving said conveyor; a plurality of magnets having pole faces of alternate polarity disposed closely adjacent to the upper side of parts of said submerged portion and said non-submerged portion of said conveyor for producing a continuous magnetic field having successive sections of opposite polarity on the opposite side of said conveyor; means for feeding material to be separated to said tank and causing it to come in close proximity to the underside of said conveyor in said magnetic field whereby said magnetic field causes magnetic material in said mixture to engage and be carried along by said conveyor; and magnet means located below said conveyor adjacent to the discharge end thereof and above the surface of the liquid in said tank and cooperating with said pole faces for producing a high intensity magnetic field adjacent thereto through which material carried along by said conveyor must pass and within which the material will concentrate thus expediting the removal of the liquid; said means including a non-magnetic member or shield adjacent to but spaced from said conveyor.

3. In a magnetic separator for separating magnetic and non-magnetic material such as ore concentrates and middlings from each other and/or from tailings, the combination of: a reservoir or tank; means for supplying liquid to said tank; a flexible non-magnetic conveyor having a portion of substantially catenary shape a part of which is submerged in the liquid in said tank; said conveyor having a portion of the catenary part thereof adjacent to the discharge end of the conveyor disposed above the surface of said liquid; means for moving said conveyor; a plurality of magnets having pole faces disposed closely adjacent to the upper side of parts of said submerged portion and said non-submerged portion of said conveyor for producing a continuous magnetic field on the opposite side of said conveyor; means for feeding material to be separated to said tank and causing it to come in close proximity to the underside of said conveyor in said magnetic field whereby said magnetic field causes magnetic material in said mixture to engage and be carried along by said conveyor; a member formed of permeable material located above the surface of the liquid in said reservoir and below said conveyor adjacent to the discharge end thereof and intermediate two of said pole faces and cooperating with said pole faces for producing a high intensity magnetic field through which material carried along by said conveyor must pass; and a non-magnetic member or shield located above said last-named member.

4. In a magnetic separator for separating magnetic and non-magnetic material such as ore concentrates and middlings from each other and/or from tailings, the combination of: a reservoir tank; means for supplying liquid to said tank; a flexible non-magnetic conveyor having a portion of substantially catenary shape a part of which is submerged in the liquid in said tank; said conveyor having a portion of the catenary part thereof adjacent to the discharge end of the conveyor

disposed above the surface of said liquid; means for moving said conveyor; a plurality of magnets having pole faces of alternate polarity disposed closely adjacent to the upper side of parts of said submerged portion and said non-submerged portion of said conveyor for producing a continuous magnetic field having successive sections of opposite polarity on the opposite side of said conveyor; means for feeding material to be separated to said tank and causing it to come in close proximity to the underside of said conveyor in said magnetic field whereby said magnetic field causes magnetic material in said mixture to engage and be carried along by said conveyor; a member formed of permeable material located intermediate two of said pole faces and below said conveyor adjacent to the discharge end thereof and above the surface of the liquid in said tank and cooperating with said pole faces for producing a high intensity magnetic field along opposite sides of said member; and a member or shield interposed between said conveyor and said last-named member and forming with said conveyor an aperture through which material carried along by said conveyor must pass.

5. In a magnetic separator for separating magnetic and non-magnetic material such as ore concentrates and middlings from each other and/or from tailings, the combination of: a reservoir or tank; means for supplying liquid to said tank; two horizontally spaced rollers or drums; a flexible non-magnetic continuous conveyor or belt extending around said rollers and having a portion of the lower reach thereof submerged in the liquid in said tank and a portion of said reach adjacent one end disposed above the level of said liquid, said end constituting the discharge end for magnetic material or concentrates; means for causing said conveyor to travel about said rollers in such a direction that said lower reach travels towards said discharge end; a plurality of magnets having pole faces of alternate polarity disposed closely adjacent to the upper side of a part of said portions of the lower reach of said conveyor both above and below the surface of said liquid for producing a continuous magnetic field having successive sections of opposite polarity on the opposite side of said conveyor; means for feeding material to be separated to said tank and causing it to come in close proximity to the underside of said conveyor in said magnetic field whereby said magnetic field causes magnetic material in said mixture to be carried along by said conveyor; a bar of permeable material located intermediate two of said pole faces and above the water in said tank and below said conveyor adjacent to the discharge end and extending transversely thereof for producing a high intensity magnetic field through which the material carried along by said conveyor must pass; and a non-magnetic shield above said permeable bar but spaced from said conveyor.

6. In a magnetic separator for separating magnetic and non-magnetic material such as ore concentrates and middlings from each other and/or from tailings, the combination of: a non-magnetic conveyor; means for moving said conveyor; a plurality of stationary magnets having pole faces disposed closely adjacent to the upper side of parts of said conveyor for producing a magnetic field on the opposite side of said conveyor; means for causing a liquid containing material to be separated to come into close proximity to the underside of said conveyor in said magnetic field whereby said magnetic field causes magnetic ma-

REFERENCES CITED

material in the mixture to be drawn to and carried along by said conveyor; a magnet member located adjacent to the discharge end of the conveyor at the side opposite to said magnets but within the magnetic field produced thereby whereby a comparatively narrow highly magnetized air gap is formed through which the material must pass and within which the material will be dewatered by rearrangement of the particles thereof before being discharged; and a non-magnetic member or shield located immediately above said magnet member.
